UNITED STATES PATENT OFFICE.

ARTHUR J. FIX, OF BUFFALO, NEW YORK.

MACHINE FOR SHARPENING RAZOR AND OTHER BLADES.

1,144,467.

Specification of Letters Patent. Patented June 29, 1915.

Application filed May 20, 1912. Serial No. 999,492.

To all whom it may concern:

Be it known that I, ARTHUR J. FIX, a citizen of the United States, residing at Buffalo, in the county of Erie and State of New York, have invented a new and useful Improvement in Machines for Sharpening Razor and other Blades, of which the following is a specification.

This invention relates to machines for 10 sharpening or stropping razor and other blades, and more particularly to machines of that type which are adapted for sharpening safety razor blades and in which both sides of the blades are sharpened simultaneously.

The objects of the invention are to produce a machine of this kind which is adapted to operate upon a plurality of blades at one time and which is provided with a 20 holder into which the blades can be easily inserted and from which they can be readily removed when sharpened, and which can be readily placed in sharpening position in the machine; also to produce a holder of this 25 kind which can be easily adapted to accommodate various kinds of safety razor blades; also to provide a machine of this kind with means for insuring an even wear on all portions of the sharpening devices and a uniform 30 sharpening of all of the blades; also to provide means for readily positioning the holder relatively to the sharpening devices to enable the same to operate on blades of different widths; also to improve machines 35 of this kind in the respects hereinafter more fully specified.

In the accompanying drawings, consisting of two sheets; Figure 1 is a plan view of a machine embodying the invention. 40 Fig. 2 is a side elevation thereof. Fig. 3 is an end elevation thereof, on an enlarged scale. Fig. 4 is a transverse sectional elevation thereof on line 4—4, Fig. 1. Fig. 5 is a side elevation of the holder for the blades. 45 Figs. 6 and 7 are fragmentary longitudinal sectional elevations of the holder, on an enlarged scale, on line 6—6, Fig. 4, showing the holder provided with two different kinds of safety razor blades. Fig. 8 is a 50 sectional elevation of the holder on line 8—8, Fig. 5. Fig. 9 is a fragmentary transverse sectional elevation, on an enlarged scale, showing a gage for positioning the holder relatively to the sharpening devices. 55 Fig. 10 is a side elevation of the gage. Fig. 11 is a plan view thereof. Fig. 12 is a sec-

tion on line 12—12, Fig. 11, showing a gage plate in place in the gage. Fig. 13 is a fragmentary perspective view of the gage plate.

Like reference characters refer to like parts in the several figures.

A represents a rectangular box-shaped casing or housing of the machine having side and end walls a a' and which may be 60 provided with lugs a² for securing the machine to a suitable base.

B represents sharpening rolls which may be of any suitable construction, but which are preferably provided with strips b of leather or other suitable material for sharpening or stropping cutting edges, and which are wound helically on the surfaces of the two rolls in such a manner that the strip on each roll will enter into the groove or space 65 between the convolutions of the strip on the other roll. The rolls are mounted on shafts b' which are suitably journaled in the end walls of the casing A and which are connected by suitable gears or other means 70 which cause them to revolve in opposite directions. The rolls may be rotated in any suitable manner, for example, by a pulley b² secured to one of the shafts and which may be connected by a belt (not shown) to any 75 suitable source of power.

The casing A is preferably provided with suitable cover plates C C' which are removably secured to the casing by suitable means, such as screws c engaging in key-hole slots 80 c' in the cover plate, so that the plates can be easily removed from the casing to afford access to the rolls. The plates do not entirely close the casing, but leave an opening 85 through which the holder and the articles to be sharpened can be inserted. All of these parts are common in machines of this type and may be of any suitable or desired construction.

For supporting the razor or other blades 100 which are to be sharpened, in the proper position to be acted upon by the sharpening rolls, a holder is provided which comprises two clamping members D D' which are pivotally connected or hinged at d and 105 which have engaging faces or jaws d' and d² between which the blades are adapted to be clamped. These jaws are pressed toward each other by suitable springs d² and may be separated to release the blades by 110 pressing together two upwardly extending arms or extensions d² which are formed in-

tegral with or otherwise secured to the two jaws of the holder. One or both of the jaws of the holder are preferably provided with suitable hooks or extensions d^5 formed 5 on or located adjacent to the engaging faces which are adapted to engage in recesses or holes in the blades to securely hold the same and prevent them from being drawn out of the holder and between the rolls. These 10 hooks may be formed integral with the jaws of the holder, or, as shown in the drawings, they may be formed on a holding plate d^6 which may be removably secured to the inner face of one of the jaws in any suitable 15 manner, for instance by screws d^7 . By providing a holding plate for each of the different kinds of blades to be sharpened, the holder can readily be adapted for any kind of blade by securing the proper face plate 20 on the jaw, see Figs. 6 and 7.

In Figs. 4, 5 and 6 the holder is shown provided with the usual "Autostrop" safety razor blades E, and in Fig. 7 with the "Gillette" safety razor blades E'. If desired, 25 the hooks or extensions can be formed integral with the holders and a different holder provided for each of the different kinds of blades.

The holder extends longitudinally of the 30 machine and is supported above the valley or groove between the rolls in such a manner that it can be adjusted toward and from the rolls. For this purpose the holder is provided at its opposite ends with extensions or arms f , which are adapted to rest in suitable supports F, secured to or formed integral with the end walls of the casing. These supports have vertical guide slots f' which are open at their upper ends and 40 which are adapted to receive the arms f of the holder and in which these arms can be adjusted to raise or lower the holder relatively to the sharpening rolls.

Any suitable means may be provided for 45 adjusting the holder relatively to the rolls to adapt the same to operate on blades of different widths. In the construction shown for this purpose, adjusting levers G are provided which are pivoted at g to the supports F. These levers are movable vertically relatively to the supports and preferably move in slots g' in the supports F. The levers extend across the lower portion of the slots f' , so that the arms f of the 55 holders rest on the levers. The free ends of the levers are provided with set screws g^2 by means of which the levers can be raised or lowered as required and suitable lock nuts g^3 may be provided for holding 60 the set screws in the desired position. By turning the set screws the holder may be moved toward or from the rolls as may be required by the width of the blades which are to be sharpened.

65 In order to cause an even wear of the

sharpening rolls throughout their length and also to insure an equal sharpening of all portions of the blades, the holder with the blades carried thereby is moved back and forth lengthwise of the rolls during the 70 operation of the machine. Any suitable mechanism can be employed for this purpose, that shown in the drawings comprising a lever H which is suitably pivoted at h on a bracket h' , suitably secured to the 75 frame of the machine. The upper end of this lever has a loose connection with the arm f of the holder. A worm h^2 is secured to one of the shafts b of the machine and engages with a worm gear h^3 which is suitably journaled on the bracket h' and which has a pin h^4 secured in the side thereof which engages in a slot in the lower arm of the lever H. When the machine is being operated the movement of the gear h^3 causes 85 the lever to swing on its pivot and thus reciprocate the holder and the blades carried thereby.

The blades used in safety razors of different kinds vary considerably in size and 90 shape, and it is therefore desirable to provide means for readily determining the height above the rolls to which the holder should be adjusted for properly positioning the particular blades which are to be sharpened. A gage I is preferably provided for 95 this purpose which comprises a block or body portion i which has two faces i' i'' which have substantially the same curvature as the periphery of the sharpening rolls. The gage has a central slot i^2 into which a blade can be inserted, and is provided with means for holding the blade in the slot, such as a cam i^3 , which can be pressed into engagement with the blade by a thumb screw i^4 , the end of which engages with the cam. After the blade has been placed in the gage with its edge projecting slightly beyond the lower edge thereof and secured in place therein, the upper portion of the 100 blade, which will project above the gage, may be secured to the holder. Two of these gages are preferably used, one to each end of the holder. The holder is then placed in position on the machine so that the gages 105 at their opposite ends rest in the groove between the two sharpening rolls. The adjusting levers G are then set to support the holder in the position in which it is held by the gages. The holder can then be removed from the machine and the blades with the gages attached thereto can then be removed from the holder and replaced by blades to be sharpened. The gages can readily be removed from the blades by 110 loosening the screw i^4 and the cam i^3 operated thereby. Springs i^5 secured on the upper faces of the gages press against the holder to take up any lost motion between the gages and the holder and insure the 115 120 125 130

proper positioning of the holder relatively to the sharpening rolls.

Instead of clamping some of the blades to be sharpened in the gages to adapt the gages to be used for properly positioning the holders relatively to the sharpening rolls, gage plates K can be employed which are adapted to be inserted into the slot in the gage and which are adjustable within the slots to enable the gage to be set for different blades to be sharpened. These gage plates are shown in Figs. 12 and 13 and are provided at their edges with suitable graduations, such as notches k, each of which corresponds to a certain kind or make of blade and the plate is so adjusted in the gage that the proper graduation for the kind of blade to be sharpened is opposite the upper edge of the gage. In order to facilitate this adjustment, the gage plate is provided at one side with a rack k', with which a worm k² secured to a pin k³ journaled in the gage, engages. By turning the pin, the plate can be raised or lowered in the gage. The gage plates may be provided at their upper ends with any usual or suitable means for securing them in the holders.

While the machine described is adapted more particularly to operate upon a plurality of safety razor blades of any suitable kind, it will be understood that the machine is not limited to this use but can also be used for sharpening other cutting edges and can, if desired, be used to operate upon any one safety razor blade at a time.

The described machine has the advantage that it can be very easily operated and that it sharpens the blades very rapidly owing to the fact that the rolls act on both sides of the blade at the same time. The blades can be very easily inserted into the holder and released therefrom and are securely held therein during the sharpening operation. The machine is therefore capable of sharpening a large number of blades in a short time, since very little time is required to change the blades. The machine can be easily adapted to operate on the various standard kinds of safety razor blades now manufactured and the holder could easily be constructed to hold other cutting edges or knives if desired. The reciprocatory motion of the holder facilitates the sharpening of the blades and greatly lengthens the life of the rolls, since it insures an even wear over all parts of the rolls and prevents the formation of grooves or ruts around the periphery of the rolls. The gages are also easily operated and enable the machine to be readily adjusted to operate on different kinds of blades.

I claim as my invention:

1. In a machine for sharpening blades, the combination of a sharpening roll jour-

naled on the machine, a holder for a blade to be sharpened, said holder having projecting supporting ends, parallel upright guide parts on said machine between which the holder can be lowered to bring the blades 70 into operative relation to said roll, levers extending across said guide parts and upon which the ends of said holders are adapted to rest, and means for adjusting the levers vertically.

2. In a machine for sharpening blades, the combination of a sharpening roll journaled on the machine, a holder for a blade to be sharpened, said holder having projecting supporting ends, parallel upright 80 guide parts on said machine between which the holder can be lowered to bring the blades into operative relation to said roll, means for reciprocating said holder, and co-operating parts on said means and said holder which are adapted to be connected when the holder is lowered into operative relation between said guide parts.

3. In a machine for sharpening blades, the combination of a sharpening roll journaled on the machine, a holder for a blade to be sharpened, said holder having projecting supporting ends, parallel upright guide parts on said machine between which the holder can be lowered to bring the blades 90 into operative relation to said roll, a reciprocating member actuated by the rotation of said roll, and a part on said holder adapted to be moved into operative engagement with said reciprocating member when 100 said holder is lowered between said guide parts.

4. In a machine for sharpening razor blades, the combination of a casing, a pair of parallel sharpening rolls journaled in 105 said casing, a holder for a blade to be sharpened, said holder having projecting supporting ends, parallel upright guide parts on said casing between which said holder can be lowered to bring the blades into operative relation to said rolls, adjusting levers pivoted at one end on said guide parts and adapted to support said holder, and means for adjusting the free ends of said 110 levers vertically for limiting the movement 115 of the holder relatively to said rolls.

5. In a machine for sharpening razor and other blades, and having a frame and a pair of parallel sharpening rolls, of a holder for said blades which extends longitudinally of 120 said rolls above the groove between them, supporting devices for said holder, said supporting devices having vertical slots in which the ends of said holder are adapted to rest, levers extending across said slots 125 and upon which the ends of said holder are adapted to rest, and means for adjusting the positions of said levers vertically for adjusting the position of said holder, substantially as set forth.

6. In a machine for sharpening blades, the combination of a sharpening roll journaled on the machine, a holder for a blade to be sharpened, said holder having projecting supporting ends, parallel upright guide parts on said machine between which the holder can be lowered to bring the blades into operative relation to said roll, means for reciprocating said holder, coöperating parts on said means and said holder which are

adapted to be connected when the holder is lowered into operative relation between said guide parts, and means for adjusting said holder relatively to said roll.

Witness my hand, this 13th day of May, 1912.

ARTHUR J. FIX.
